UNITED STATES PATENT OFFICE.

ROBERT J. CARSON, OF OMAHA, NEBRASKA, ASSIGNOR OF ONE-THIRD, BY MESNE ASSIGNMENTS, TO THE UNION HYDRAULIC DRAIN TILE COMPANY, OF SAME PLACE.

DRAIN-TILE-MAKING MACHINE.

SPECIFICATION forming part of Letters Patent No. 352,448, dated November 9, 1886.

Application filed December 11, 1885. Serial No. 185,352. (No model.)

To all whom it may concern:

Be it known that I, ROBERT J. CARSON, a citizen of the United States, residing at Omaha, in the county of Douglas and State of Nebraska, have invented a new and useful Drain-Tile-Making Machine, of which the following is a specification.

My invention relates to improvements in drain-tile-making machines in which the concrete or other material used is thoroughly worked and packed into a shell provided, having a rotary motion and so constructed as to easily allow the tile to be removed from said shell when completed; and it consists in the improved construction and combination of parts, as will be hereinafter more particularly described and pointed out in the claims.

Figure 1 is a side elevation of the machine. Fig. 2 is front elevation of the machine, or the side at which operator controls machine. Fig. 3 is a top view of machine. Figs. 4 and 5 show, respectively, a plan and sectional view of flexible core; Fig. 6, detail views of packing-rod guides; and Fig. 7, detail arrangement for giving required rotary motion to core-protector; Fig. 8, lever for starting receiving-shell K and revolving table I downward.

Referring to the accompanying drawings, in which the same letters of reference indicate corresponding parts in all the figures, A A represent the standards of the machine, each of which, together with the cross-pieces a a, are made of one piece. These standards are secured to each other by means of additional cross-pieces, b b, upon the front and rear portion of the machine. Upon the front part of this frame a table, R, is movably secured by means of the vertical guideways s s', one upon each side of the machine. Two counter-weights, S S, are secured to the sides of the table by means of two ropes or cords, which pass over pulleys b' b'. The forward part of this table is made round, so as to permit of easy access to the machinery, and it is also provided in its top with a hole or aperture. A revolving annular table, I, is secured upon the top of the table R by means of the flanged annular cover I². A vertical rack-bar, E, is secured upon the front cross-pieces, b, at the rear of the table, to the lower end of which is

secured the forwardly-projecting arm Or. A hollow flexible core, F, is secured to this arm by means of the rod St, and projects through the holes in the tables R and I.

Secured to the top of the frame, by means of the forwardly-projecting bracket V, is a core-protector, Q, which extends down to the top of the table I when said table is in its raised position. Around this protector is a hopper, J, which is of the same length as the core-protector Q, and has its upper end made flaring to receive the concrete or other material out of which the tile is to be made. Secured to the bracket V, by means of the bolt m', and extending down over the top of the protector Q, by means of the arms w', is an annular guide, v', having notches t' upon its inner side. Fitting around the lower end of the hopper J, and resting upon the table I, is a shell, K, which is slightly longer than the length of the tile to be made.

Pivoted to the top of the frame is a series of levers, O, to the front ends of which are secured an equal number of tamping or packing-bars, P. The lower ends of these bars are provided with laterally-projecting feet or cross-heads, which move up and down between the core F and shell K. This construction of the ends of the tamping-bars presents a greater surface for packing the tile material, and also prevents it from falling through onto the table beneath when the machine is at rest. The intermediate portions of these bars pass through the notches t' in the guide v', which causes them to always move in their proper places.

Secured to the cross-pieces b b, by means of suitable bearings, is a vertical shaft, H, to the upper end of which is secured the gear-wheel t, and upon the lower end is movably secured, by means of a feather, the gear-wheel u. The wheel t engages with an annular cog-wheel, v, around the hopper J, and the wheel u with cogs w around the periphery of the table I. These two gear-wheels cause the hopper and shell to revolve in unison, while the core-protector can be caused to revolve with them or in the opposite direction by means of a casting, W, secured to its top. The upper edge of this casting is provided with teeth X, which can be made inclined in either direction as

it is desired to cause the core-protector to revolve, which teeth are actuated by means of a catch, a' , pivotally secured to a crank, c' , one end or arm of which is secured to one of the levers O . By this rotary motion of the protector and hopper and shell the bars P are kept more cleanly, and the concrete is kept from adhering to the hopper or protector, and the tile has a smoother and better surface 10 when completed.

Secured to the rear part of the machine, by means of the hangers e , is a counter-shaft, B , upon which are placed three pulleys, f , g , and h . Power which is applied to this counter-shaft through the belting i is transmitted 15 through the belting j to main shaft c , upon which are placed the face-pulleys r x k , and also the sprocket-pulley l . From the shaft c power is transmitted to the levers O through 20 the pulley y on the shaft or stud L , the eccentrics M , which are connected with the pulley y by a suitable train of gearing, and through the rods N , one end of each of which is connected with one of the eccentrics M on the 25 shaft d' , and the other end with the end of one of the levers O . Power is also transmitted from the shaft c to the hopper J and table I through the pulley Nn and gear-wheels s s ; or an intermediate shaft, G , can be used and one 30 of the gears s be secured to the end of it. As it is desired to move the rack-bar E either up or down, power is applied to it through the reversing mechanism, consisting of two intermeshing pinions, z and n , which are secured 35 upon the lower end of a lever, Z . The lower one of these pinions, z , is operated by means of the sprocket-pinion m , which is connected with the sprocket-wheel l on the shaft c by means of the chain i' . A shaft, D , is journaled to the 40 cross-pieces a a , and is provided with a spur-wheel or pinion, p , at one end, which engages with the rack E , and with a cog-wheel, o , at the other. The lever Z is pivotally secured to one of the cross-pieces a in such a position 45 that by moving its upper end by means of the rack-bar lever e' the pinions z and n can be made to alternately engage with the cog-wheel o , or be thrown out of engagement with it entirely. When it is desired to move the rack-bar E in one direction, the gear n is made to 50 engage with the wheel o , as shown in Fig. 1, but when it is desired to move it in the other direction, the gear z is made to engage with it, and the gear n runs idly upon its bearing. 55 The lever e' is retained in either position by means of a notch which engages with the staple r' .

As the tile is formed by the accumulation of concrete or other material between the hopper 60 and core protector, or between the shell and core, rather, the table R is gradually forced downward, carrying with it the shell K around the core F . A lever, T , is secured at one end to the under side of the journal-box U , and at 65 its outer end is provided with a hand-hold, by means of which the operator can start the table R and shell K downward when the tile is first

started. After the tile has been formed, the core F is withdrawn from the interior by causing one of the gears z or n to engage with the cog-wheel o . The shell K , with the inclosed tile, is then removed from the table, and an empty shell put in its place. The lever Z is then shifted so as to throw that gear out of engagement with the wheel o and the other gear 75 in. This causes the rack-bar E to move in the opposite direction, and to take the table up with it into its first position, when the same process is again repeated. The tile is easily removed from the shell K by inverting the 80 shell and letting the tile fall the distance that the shell is longer than the tile, which will so loosen it that the shell can then be removed by lifting it upward, and letting the tile remain in its place to dry. 85

To facilitate the removal of the core F from the interior of the tile, it is made contractible, and consists of a sheet of metal having its edges united at one side in a butt-split joint, x' . Secured upon the inner sides of this core are 90 two ribs, $y' y'$, one of which is at the joint x' and the other is directly opposite. Near each end of one of these ribs is an offset or loop, within which are secured the rings $g' g'$. Secured to the opposite sides of these rings is a 95 rod, h' , which keeps them at the same distance apart, and causes them both to operate together in expanding or contracting the outer shell. To the lower ring and to the lower end of the core a coiled spring is secured, which also assists in contracting the core. The core is secured to the top of the rod St by means of a short arm, which connects it with the top ring. When the rod St is forced upward, it causes the movable sides of the rings to press against the 105 rib at that side and forces it outward, thus expanding the core, while if the rod is drawn downward it withdraws that side of the rings from the rib and causes the core to collapse. The upper end of this core is made slightly 110 tapering, so as to more readily enter the lower end of the core-protector, and thus prevent the escape of concrete at that point.

Having thus described my invention, I claim and desire to secure by Letters Patent 115 of the United States—

1. The combination of a frame having a vertically-moving table secured to its front side, said table being round on its front side and having a hole or aperture in its top, a core 120 projecting upwardly through said hole, a hopper above said table and around said core, a shell upon said table and around the lower end of said hopper, a series of tamping-bars between said hopper and said core, and means, substantially as described, for operating said tamping bars and for moving said table and core. 125

2. The combination of a frame having a vertically-moving table secured to its front side, an annular cover secured to the top of said table, a revolving table between said cover and said vertically-moving table, a core projecting upwardly through said tables, a hop- 130

per above said tables and around said core, a shell upon said revolving table and around the lower end of said hopper, a series of tamping-bars between said hopper and core, and 5 means, substantially as described, for operating said bars, tables, and core.

3. The combination of a frame having a vertically-moving table secured to its front side, a revolving table movably secured upon the 10 top of said vertically-moving table, a core projecting upwardly through said tables, a hopper above said tables, a core-protector within said hopper and around the upper end of said core, a series of tamping-bars between said 15 hopper, core, and core-protector, and means, substantially as described, for operating said bars, tables, and core.

4. The combination of a frame having a vertically-moving table secured to its front side, 20 a revolving table secured to the top of said vertically-moving table, a core projecting upwardly through said tables, a hopper above said tables having an annular cog-wheel around its intermediate portion, a shell around the 25 lower end of said hopper and resting upon said revolving table, a vertical shaft at the side of said hopper having a gear-wheel at its top engaging with said annular cog-wheel and another gear-wheel secured to its lower end by 30 means of a feather engaging with said revolving table, a series of tamping-bars between said hopper and said core, and means, substantially as described, for operating said bars, shaft, table, and core.

35 5. The combination of a frame having a vertically-moving table secured to its front side, a core projecting upwardly through said table, a hopper above said table, a core-protector within said hopper and around the upper end 40 of said core, a casting secured to the top of said core-protector having teeth upon its upper edge, a crank having one of its arms provided with a catch or pawl engaging with said teeth, a series of tamping-bars between said 45 hopper, and said core-protector, and means, substantially as described, for operating said bars, crank, and table.

6. The combination of a frame having a vertically-moving table secured to its front side, 50 a core projecting upwardly through said table, a hopper, a core-protector within said hopper, an annular guide having notches upon its inner side and secured at the top of said core-protector by means of vertical arms and a bolt, 55 a series of tamping-bars around said core-protector within the notches in said guide, the lower end of said bars being provided with laterally-extending feet, and means, substantially as described, for operating said bars, 60 table, and core.

7. The combination of a frame having a vertically-moving table secured to its front side, a rack-bar secured to the front cross-pieces of said frame, a forwardly-projecting arm secured to the lower end of said rack-bar, a rod 65 secured to the end of said arm, a core secured

to said rod and projecting upwardly through said table, a hopper above said table, a series of tamping-bars between said hopper and said core, and means, substantially as described, 70 for operating said rack-bar and tamping-bars.

8. The combination of a frame having a vertically-moving table secured to its front side, a rack-bar secured to the front cross-pieces of said frame, a core secured to said rack-bar and 75 projecting upwardly through said table, a hopper, a series of tamping-bars between said hopper and said core, a lever pivotally secured to said frame, two intermeshing pinions secured to the lower end of said lever, either of said 80 pinions being adapted to engage with and operate said rack-bar, and means, substantially as described, for operating said tamping-bars and said pinions.

9. The combination of a frame having a vertically-moving table secured to its front side, a core, a hopper, a shell around the lower end of said hopper, a series of tamping-bars, a lever secured at one end to said frame and resting upon the top of said shell and having a 90 hand-hole at its outer end, and means, substantially as described, for operating said tamping-bars and said core and table.

10. A core for tile-machines, consisting of a sheet of metal having its edges united at one 95 side in a butt-split joint, two vertical ribs upon the inner side of said core, one of which is at said joint and the other is directly opposite, one of said ribs being provided near each end with an offset or loop, a ring in each of said 100 loops, a rod projecting within said core, and an arm for securing said rings to said rod.

11. A core for tile-machines, consisting of a sheet of metal having its edges united at one side in a butt-split joint, two vertical ribs 105 within said core, one of said ribs being at said joint and the other directly opposite, one of said ribs being provided near each end with an offset or loop, a ring in each of said loops, a rod connecting said rings at the other side, a 110 spring connected to the lower ring and to the lower end of said core, a rod projecting within said core, and an arm connecting the upper ring with the top of said second rod.

12. The combination of a frame having a 115 vertically-moving table secured to its front side, a collapsible core projecting upwardly through said table, a hopper, a series of levers pivotally secured to the top of said frame, a core-protector within said hopper, a tamping-bar secured to the end of each of said levers and working between said hopper and said core-protector, a crank secured by one arm to one of said levers, having a catch on the other arm engaging with teeth in the upper end of 120 said core-protector, and means, substantially as described, for operating said levers, table, and core.

ROBT. J. CARSON.
